UNITED STATES PATENT OFFICE

109,300

DESIGN FOR A PLASTIC TUBE OR SIMILAR ARTICLE

Alan F. Harvey, Kearny, N. J., assignor to E. I. du Pont de Nemours & Company, Wilmington, Del., a corporation of Delaware

Application April 2, 1937, Serial No. 68,529

Term of patent 7 years

To all whom it may concern:

Be it known that I, Alan F. Harvey, a citizen of the United States, and a resident of Kearny, in the county of Hudson and State of New Jersey, have invented a certain new, original, and ornamental Design for a Plastic Tube or Similar Article, of which the following is a specification, reference being had to the accompanying drawing, forming part thereof.

In the accompanying drawing:

The figure is a front elevational view slightly in perspective of a section of a plastic tube or similar article showing my new design.

I claim:

The ornamental design for a plastic tube or similar article, substantially as shown.

ALAN F. HARVEY.
